(57) **CLAIM**

The ornamental design for rib reinforced tow hitch chain retainer, as shown and described.

DESCRIPTION

FIG. 1 is a top right perspective view of the rib reinforced tow hitch chain retainer of my new design.

FIG. 2 is a front view of the rib reinforced tow hitch chain retainer of FIG. 1.

FIG. 3 is a rear view of the rib reinforced tow hitch chain retainer of FIG. 1.

FIG. 4 is a right side view of the rib reinforced tow hitch chain retainer of FIG. 1.

FIG. 5 is a left side view of the rib reinforced tow hitch chain retainer of FIG. 1.

FIG. 6 is a top view of the rib reinforced tow hitch chain retainer of FIG. 1; and,

FIG. 7 is a bottom view of the rib reinforced tow hitch chain retainer of FIG. 1.

The features shown in dashed lines form no part of the design and are not claimed.
